UNITED STATES PATENT OFFICE.

FREDERICK W. BARNES AND GEORGE F. PHILLIPS, OF ROCHESTER, NEW YORK,
ASSIGNORS TO EASTMAN KODAK COMPANY, OF ROCHESTER, NEW YORK, A COR-
PORATION OF NEW YORK.

PHOTOGRAPHIC-DARK-ROOM LAMP.

1,252,383.

Specification of Letters Patent. Patented Jan. 8, 1918.

Application filed January 8, 1917. Serial No. 141,202.

To all whom it may concern:

Be it known that we, FREDERICK W. BARNES and GEORGE F. PHILLIPS, of Rochester, in the county of Monroe and State of New York, have invented certain new and useful Improvements in Photographic-Dark-Room Lamps; and we do hereby declare the following to be a full, clear, and exact description of the same, reference being had to the accompanying drawings, forming a part of this specification, and to the reference-numerals thereon.

Our present invention relates to photography, and more particularly to photographic dark room lamps, and has for an object to provide a compact, economical, simple and efficient, portable electric lamp for general amateur use, having a permanently attached socket and plug member which may be screwed, without extra attachments, or any manipulation of the contained electric bulb, directly into any convenient wall bracket or drop cord electric socket, so that it may be used in any position, although preferably suspended vertically; and to provide an improved arrangement and simple construction of casing, windows and their retaining members and light protective means, which permit easy removal and assemblage of selected filter elements, but prevent escape of undesired actinic light from the lamp during use of the device, while furnishing an efficient source of general illumination for the dark room and a dim safe light for the work bench.

To this and other objects, which are apparent from the following disclosure, the invention consists in certain improvements and combination of parts, all as will be hereinafter more fully described, its novel features being pointed out in the claims at the end of the specification.

In the drawings: Figure 1 is a perspective of the dark room lamp.

Fig. 2 is a plan view of the bottom window and the retaining device therefor, detached from the casing.

Fig. 3 is an enlarged bottom plan view, with the circular window in place.

Fig. 4 is a vertical section through the lamp, the front window being partially withdrawn and the bottom window and its

locking member removed from their normal positions.

Fig. 5 is a section taken on the line A—A 55 of Fig. 3, illustrating the construction of the bottom window and frame.

Fig. 6 is an enlarged vertical section showing the construction of the hinge for the light locking cap over the large window. 60

Similar reference numerals throughout the several figures indicate the same parts.

As a practical embodiment of our invention, we provide a lamp casing 1, formed of suitable sheet material, such as metal, bent 65 into an exaggerated semi-cylindrical shape, the curved portion of the casing forming a reflector 2 and the flat portion serving to hold a large rectangularly shaped window 3, the reflector and the window combining 70 to throw the bulk of the light into the room for general illumination. Fastened to the top 4 there is an electric plug and socket attachment 5 permitting quick connection with an electrical fixture without unassembling the dark room lamp, and in the window end of top 4 an aperture 6, having a light proof door 7 thereover, is provided for insertion of the front window into the casing, actinic light being prevented from leaking between the window and the frame by the special construction hereinafter described. The bottom 8 carries a removable circular window 9 constituting a light filter adapted to transmit a dim safe light downwardly to a work bench and photographic material being treated thereon. 85

The plug and socket attachment 5, comprises a metal casing 10 screw threaded on its outer end 11 for attachment to an electrical fixture, and screw threaded on its inner end 12 to form a socket for insertion of an electric bulb 13. Concentric within the casing 10 and separated therefrom by insulation 14, extending from the upper end of 95 casing 10 to the inner screw threaded part 12, is a conductor or post 15 projecting outwardly to constitute a terminal to coöperate with the plug part 11 and projecting slightly into the screw threaded socket 12 to coöperate with the latter to carry the current to the lamp. This plug and socket attachment 5 is permanently fixed to the top 4 of the casing 1, by means of an insulating tube 16 100

engaging the casing of the fixture 5, around which a collar 17, L shaped in cross section is pressed or crimped, the flange of this collar 17 being fastened to the top 4 by solder 5 or other suitable means.

The two window filters 3 and 9 comprise one or more layers, 18 and 19 (see Fig. 5) of light transmitting material, such as film base, paper, cloth or the like, between two 10 panes of glass 20 and 21, the layers 18 and 19 being suitably colored in the preferred embodiment of the invention, so that their added color values provide a safe efficient light that will not affect photographic material subjected thereto. It, of course, is clear that various types of filter construction, such as a single piece of glass or other translucent material having the desired light transmitting or restraining qualities, may be used.

15 In order that window 3 may be removed, slideways are provided on opposite sides of the window, these being formed by flanges 22 and 23 projecting inwardly on either side of the casing 1, and flanges 24 and 25 on the 20 bottom, thereby holding the window in place and preventing escape of light around its side and bottom edges. Flanges 26 and 27 projecting downwardly from the top 4 and coöperating with the casing walls provide 25 sides to an aperture through which the window 3 may be removed. To prevent light leaking between the window and the flanges 26 and 27, and to prevent accidental removal of the window, a light proof door 7 is hinged 30 along the forward edge of the top 4 of the lamp casing and is adapted to lie flat on the top of the casing over the upper edge of the window. The hinge for the door 7 comprises a central portion 28 of flange 26 bent 35 in a circular form to receive the hinge pin 29, (Figs. 1 and 6) and the portions 30 of door 7 similarly bent (as shown in dotted lines in Fig. 6) to form the outer ends of the hinge to retain pin 29. The intermediate 40 portion 31 of door 7 is curved downwardly for approximately a quarter of a turn over all that part 28 of flange 26 which is turned about pin 29, this part 31 rotating about part 28 when door 7 is raised and at all times 45 forming a flange serving to prevent light escaping through the central portion of the hinge. The ends 32 of the door 7 are bent down to fit over the edge of lamp casing 1. This construction of door 7 permits easy 50 access to window 3 for removing or changing the same and serves to hold the window in place when the lamp is reversed, and at the same time provides an adequate light protector preventing undesired light escap- 55 ing from the casing when the lamp is used.

The disk shaped window 9 in the bottom of the casing is removably held in place between an annular locking member 33 fitting within a circular opening in the bottom 8 60 and an annular flange 34 on the inside of the

casing, the window being slightly larger than the opening in the casing bottom. The annular member 33 is substantially L shaped in cross section and has lateral flanges 35 projecting over the window to keep it from falling out, and in turn is fastened to the casing by means of laterally projecting ears 36 spaced around its periphery and slidably coöperating with the bottom of the casing to form a sort of bayonet joint. Cut out portions or recesses 37 in the bottom 8 are spaced similarly with the ears 36 around the window aperture, so that the ring 33 may be positioned with ears 36 in the recesses 37 and rotated to move the ears 36 behind the casing 75 bottom, thereby holding the ring 33 and the filter in place. The flange 34 is in the form of a ring, having its inner diameter somewhat less than the filter 9, and is resiliently mounted with another annular member 38, 80 which has a downwardly extending flange 39 on its inner periphery, to hold filter 9 in place, the flange 34 being fastened at its outer periphery to the inner side of bottom 8 of the casing. 90

In assembling the bottom window, the lamp casing 1 is held bottom up and window 9 placed in the annular flange formed by members 34 and 38. Ears 36 of locking frame 33 are located in the corresponding 95 openings 37 in the bottom 8 and rotated, at the same time being pressed downwardly. The resilient member 34 allows the ears 36 to be held firmly between the bottom 8 and the flange of annular ring 33, thereby clamping 100 the window 9 between member 33 and 34. A struck up protuberance 40 forms a stop for one of the ears 36, preventing member 33 from being rotated too far and thereby accidentally unlocking and releasing window 9. 105 It can readily be seen that this forms an efficient light proof door which can be operated easily and quickly in the dark if necessary.

This combination makes a simple portable 110 lamp, which may be screwed directly into any convenient electric lamp socket without opening the lamp, or changing the fixtures in any way. It is as convenient to handle as a single electric bulb, as none of the adjustments to the lamp and casing hitherto necessary in dark room lamps are required. 115

We claim:

1. A portable dark room lamp comprising 120 a non-actinic casing, an electrical fixture for an electric bulb, said casing having an opening in a wall for a filter window and recesses adjacent said opening, and a rotatable annular member to hold a window slightly larger than said opening, between said casing and member, said member having integral locking lugs insertible into said recesses and rotatable behind said casing wall to maintain the parts in assembled relation. 125

2. A dark room lamp comprising a non 130

actinic casing apertured for a window, slideways on opposite sides of the aperture to hold said window, said casing having an opening through a wall adjacent one end of 5 said slideways for removal and insertion of said window, and a hinged cap movable over said opening to prevent transmission of light around said windows through the opening to the exterior of the casing, the hinge 10 for the cap comprising two end lugs on the cap bent to surround a hinge pintle extending therebetween, said pintle being fixed to the casing by a projecting flange on the latter extending between the hinge lugs on the 15 cap and bent around the pintle, thereby preventing light escaping beneath the hinge pintle, said cap having a flange projecting forwardly and curved downwardly over the pintle and adapted to move around the same 20 when the cap is moved, and prevent light escaping between the cap and pintle.

3. A unitary photographic dark room lamp comprising a casing having an interior reflecting surface, two filter windows, 25 a large one opposite said reflecting surface to transmit the major portion of the light

for general illumination of a room and a small one beneath the bulb and out of line with the rays from said reflector and adapted to transmit a dim light to a work bench, an electrical fixture insulated from said casing and rigidly attached thereto, said fixture having an exterior plug adapted to be screwed into an electric light socket, and an interiorly located socket to hold an electric bulb, said casing having slideways and an opening through a wall at one end of 30 said slideways for removal and insertion of the larger window, a light proof hinged cap over said opening to prevent undesired 35 light escaping around the window to the exterior of the casing and a retaining member removably holding the small window in place.

In testimony whereof, we affix our signatures in the presence of two witnesses this 5 day of Jany., 1917.
